UNITED STATES PATENT OFFICE.

HOWARD A. WILKINSON AND WILLIAM B. NIXDORF, JR., OF ONEIDA, NEW YORK.

CONTROL FOR TAIL-LIGHTS.

1,313,847.

Specification of Letters Patent.

Patented Aug. 19, 1919.

Application filed December 14, 1917. Serial No. 207,126.

To all whom it may concern:

Be it known that we, HOWARD A. WILKINSON and WILLIAM B. NIXDORF, Jr., citizens of the United States, residing at Oneida, in the county of Madison and State of New York, have invented new and useful Improvements in Controls for Tail-Lights, of which the following is a specification.

This invention relates to controlling means for tail lamps of automobiles.

The object of the invention is to produce a device of this character, wherein the rays of light from the tail lamp will be increased or intensified, when the machine, to which the lamp is attached, is moved in a rearward direction to thus serve as a warning to persons or vehicles to the rear of the machine of the path of travel to be taken by the machine.

A further object of the invention is to produce a device of this character which shall be of an extremely simple nature and which shall be automatically actuated by the operation of the gear shift lever when the latter is moved to reversing position.

Other objects and advantages will appear as the nature of the invention is more fully understood, reference being had to the accompanying drawings, in which,

Figure 1 is a side elevation of a transmission case for automobiles, illustrating the application of the improvement thereon.

Fig. 2 is a side elevation of the resistance element.

Fig. 3 is a front elevation thereof.

Fig. 4 is an enlarged sectional view approximately on the line 4—4 of Fig. 6.

Fig. 5 is a view illustrating the manner in which the bridging block is connected to the gear shift lever of the machine, the block being in section.

Fig. 6 is a plan view illustrating the block engaging the contact fingers of the resistance element and also illustrating the electric circuit.

Fig. 7 is a sectional view approximately on the line 7—7 of Fig. 4.

On the transmission casing 10, to the rear of the gear shifting lever 11, and, of course, the table top of the said casing 10, is arranged the resistance element of my improvement. This resistance element comprises a pair of spaced uprights 12 respectively, the lower ends of which being offset and forming the same with feet 18, and suitable securing elements passed through these feet and the top of the casing 10. The mem-

bers 12, at the upper or outer portions thereof, have secured therebetween, an insulated block 14, around which is wound a resistance coil 15. To the block 14 is also secured a pair of spring contact fingers 16, the outer ends of which being flared or rounded inwardly.

On the lever 11 is secured a bridging block 16', the said block being insulated from the lever by a collar or sleeve 17 of some suitable non-electric conducting material, the block itself being, of course, in the nature of an electric conductor. Preferably, the block comprises an inner member 18 having its outer end rounded as at 19 and its inner end concaved to receive the insulator member 17. The member 18 may be constructed of any desired material and to the sides thereof is secured spring arms 20 respectively which are conductors of electricity, the said arms being rounded inwardly toward each other around the sleeve or collar 17 and having their ends extended in parallelism, as indicated by the numerals 21, a securing element, preferably in the nature of a detachable element, connecting the said extension and as shown in the drawings, this connecting element comprises a bolt or screw 22 which is engaged by a nut 23, so that by the removal thereof, the arms may be spread away from each other and the block arranged around the lever 11.

The contact fingers, as well as the resistance coil 15 are in circuit with a battery 24 and a lamp 25, the said lamp comprising a tail lamp for the machine upon which the device is installed.

Normally the current flows from the battery 24, through a conductor 26, thence through the resistance coil 15, a second conductor 27 and through the battery 25 and is returned through a conductor 28 to the battery 24. The bridging block is not designed to be brought between the contact fingers 16 until the lever 11 is swung to a position to operate the gears for reversing the car, upon which the device is arranged, and when the lever is brought to this position, as illustrated by the dotted lines in Fig. 1 of the drawings, and by the full lines in Fig. 6 of the drawings the block will be brought between the contact members, causing the current to travel from the battery, through the conductor 26, one of the contact fingers 16, through the block 16', returning through the second con-

2
tact finger, conductor 27, lamp 25, and through the conductor 28 to the battery 24, thus shunting the circuit through the resistance coil, and producing a direct current 5 from the battery to the lamp, and consequently, intensifying the rays of the lamp.

From the foregoing description, when taken in connection with the accompanying drawings, the simplicity and advantages 10 of the construction will, it is thought, be apparent without further detailed description.

Having thus described the invention, what we claim is:

15 The herein described mechanism for controlling the tail lamp of an automobile, including in combination with the gear shift lever of the machine, spaced uprights disposed adjacent to the lever, an insulated block secured between the uprights, spring 20 contact fingers on the block extending outwardly therefrom and having their free

ends rounded inwardly, a resistance coil around the block between the fingers, a lamp in electric circuit with the source of energy and with the fingers, a collar of insulating 25 material on the lever, a bridging block having its outer end rounded and its inner end concaved, and said concaved end engaging the insulated collar, spring side members connected to the bridging block and extending 30 beyond the rear portion thereof and having inturned round portions which engage with the collar and parallel extensions beyond the round portions, and a binding element between the last mentioned portions 35 for compressing the side members against the collar.

In testimony whereof we affix our signatures.

HOWARD A. WILKINSON.
WILLIAM B. NIXDORF, JR.
